DESIGN FOR A SPIN GRIP FOR ATHLETES

Katya Komarovsky, Los Angeles, Calif.

Application May 21, 1934, Serial No. 51,868

Term of patent 3½ years

To all whom it may concern:

Be it known that I, KATYA KOMAROVSKY, a citizen of the United States, residing at Los Angeles, in the county of Los Angeles and State of California, have invented a new, original, and ornamental Design for Spin Grips for Athletes, of which the following is a specification, reference being had to the accompanying drawing, forming a part thereof.

Fig. 1 is a front elevational view of a spin grip for athletes, showing my new design.

Fig. 2 is a side elevational view of the same taken on the line 2—2 of Fig. 1.

Fig. 3 is a side elevational view of the same taken on the line 3—3 of Fig. 1.

Fig. 4 is an end view taken on the line 4—4 of Fig. 1.

I claim:

The ornamental design for a spin grip for athletes as shown.

In testimony whereof I have affixed my signature.

KATYA KOMAROVSKY.
